UNITED STATES PATENT OFFICE.

GEORGE E. BRYANT, OF UTICA, NEW YORK.

SAFETY DEVICE FOR RAILROAD-LOCOMOTIVE TENDERS.

1,072,081.

Specification of Letters Patent.

Patented Sept. 2, 1913.

Application filed August 24, 1912. Serial No. 716,899.

To all whom it may concern:

Be it known that I, GEORGE E. BRYANT, a citizen of the United States, residing at Utica, in the county of Oneida and State 5 of New York, have invented a new and useful Safety Device for Railroad-Locomotive Tenders; and I do hereby declare that the following is a full, clear, and exact description of the same, reference being had 10 to the accompanying drawings, forming part of this specification.

By invention relates to a device to provide safety to firemen, or other persons on a railroad locomotive or a locomotive tender, particularly from accidents to firemen, resulting from the accidental uncoupling or breaking of the drawbar between the locomotive and the tender.

The parting or drawing away of the locomotive from the tender leaves the fireman or other persons, who may be standing or otherwise in position at or near the coupling between the locomotive and the tender, without adequate protection from falling 20 forward or otherwise, particularly when such breakage is accompanied by a shock. The accidental breakage or uncoupling of the drawbar between the locomotive and the tender, causes a breakage or uncoupling of 25 the train pipe between the locomotive and the tender, thereby suddenly applying the air brakes with full force, which action suddenly reduces or stops the momentum of the train and throwing the fireman forward 30 from the tender platform, causing serious injury to him by the fall or from being run over by the oncoming train, or both. The breakage of the connection between any of 35 the cars of a train will break the connecting air pipe between the cars, and set the brakes 40 on the train. An accidental breakage of the train pipe without breakage of the drawbar, will also set the brakes suddenly and the heavy overload on the locomotive 45 thus suddenly applied is apt to break the drawbar between the locomotive and the tender thus causing an accident to the fireman as before described. My device overcomes this liability to injury from a fall, or 50 the consequences of a fall, by providing a suitable platform and a barrier; the platform forming a safe and convenient place upon which the fireman may work and the barrier preventing him from being thrown 55 forwardly from the platform should the

inertia of the moving train be suddenly checked.

To this end my invention consists in the features of construction and combination hereinafter particularly described and 60 claimed, of which the accompanying drawings to which reference is made is an accurate description of the same, in which—

Figure 1 is an elevation, partly in section, of the rear of a locomotive and the forward 65 end of its accompanying tender, showing a longitudinal section of my device applied thereto. Fig. 2 is a plan of the "Mother Hubbard" type, so called, otherwise known as the culm burner locomotive, with its accompanying tender, showing a plan view partly in section of my device attached thereto. Fig. 3 is a side elevation partly in 70 section of the locomotive and the tender shown in Fig. 2. Fig. 4 is a rear elevation 75 of a locomotive of the type mentioned in Fig. 2 showing an elevation of the barrier of my supporting device, the platform portion of the device being shown in section. Fig. 5 is a perspective view of a form in 80 which my device may be constructed. Fig. 6 is an elevation partly in section of the so called decked type of locomotive and the tender equipped with my device. Fig. 7 is an elevation of the same locomotive and 85 tender as shown in Fig. 6, after breakage of the drawbar or coupling, showing the protective device projecting from the forward end of the tender, and indicates the method by which safety is assured to the 90 fireman or other persons. The same principle applies to all other types of locomotives with detached or detachable tenders. Fig. 8 is a front elevation of the tender 95 shown in Figs. 6 and 7 equipped with my safety device. Fig. 9 is a rear elevation of a locomotive cab shown in the elevation of Figs. 6 and 7, showing an elevation of the barrier of my device, and of the platform in section.

Referring to Figs. 1 and 5, my device consists preferably of horizontal platform 34, resting on deck 23, of the coal carrying portion of the tender, and forwardly projecting over deck 20, of the locomotive cab, 105 being provided at its forward end with an upwardly projecting barrier, containing suitable holes for firing the boiler, and the manipulation of such attachments as may be necessary for operating the locomotive. 110

This barrier extends upwardly to such a height, as may be necessary for the proper protection of the fireman, and as most of the projecting devices of the boiler are 5 above this necessary height no interference with these parts will be encountered.

On the type of the locomotive shown in Figs. 2 and 3, the engine cab being mounted forward on the boiler, the only appliances 10 projecting from the rear of the boiler are the steam gage and the water gage which are above the top of the barrier, therefore no interferences from these parts will be encountered.

15 Referring to Figs. 1 and 5, 23 is the floor or deck of the coal carrying portion of the tender. Resting on this is a framework 10, constructed preferably, though not necessarily, of longitudinal structural members 11, suitably formed to fit between the projecting water legs of the tender tank 12. These longitudinal members 11 may be bent with upwardly projecting legs 33 to form a framework for the barrier plate 13. This 20 barrier plate 13 may be formed either separately, from or integral with, platform plate 14, thus providing the platform and the barrier in one piece. If preferable, the upwardly projecting legs 33 may be formed 25 separately from horizontal legs 11, and secured thereto by any mechanical construction or means that may be deemed advisable. The upper portion 15, of legs 33, may be carried upwardly beyond the top of 30 the barrier, and securely braced to the tender tank by means of brace 16. In the type of locomotive shown in Fig. 1, this portion 15 may be preferably bent upwardly and rearwardly, to provide ample clearance 35 for the manipulation of throttle lever 17, and the other projecting devices on boiler head 18. Ample clearance 19 is allowed between the bottom of members 11, and the lower deck of the locomotive 20, to provide 40 vide for the oscillation produced by the inequalities of the road bed, and all the oscillations, swaying, etc., that may occur between the tender and the locomotive when in motion. Clearance 21 is also provided 45 between vertical leg 33, of the barrier and boiler head 18, when the locomotive and the tender are in proper relation to one another, which relation is determined by the length of drawbar 32. Cross struts 22 are provided 50 and fastened to legs 11, to add stiffness to the legs, and the entire platform 35 may be secured by bolts 24, or other suitable means, to deck 23 of tender.

Referring particularly to Figs. 4 and 5, 55 barrier plate 13 may be provided with an opening 25, which may be wide enough to allow firing doors 26, to be opened, thereby providing means for firing the boiler. Openings 27 provided with covers 28 preferably hinged, may be left in the floor of

platform 34, for manipulation of the grate levers or shaking bars. The lower portion of barrier 13 directly under firing hole 25 may be provided with a forwardly projecting ledge or apron 29, which may be formed by suitably bending this portion of part 13. This ledge 29 projects beneath the firing doors 26 and prevents coal falling between the boiler head and the barrier. In oil burning locomotives this may be dispensed with. Suitable side barriers 30, which may be attached to platform 34, by any suitable mechanical means, may be provided to prevent coal being shaken from the sides of the platform, between the locomotive and the tender. This platform and barrier 35 is subject to many modifications in construction, to adapt itself to the requirements of the different types of locomotives. If preferable, the barrier could be constructed as a 80 railing, and attached to platform 34.

Referring particularly to Fig. 1, when the wheels of the locomotive are worn down, the clearance 19 between the horizontal members 11, of platform 34, and deck 20, 90 of the locomotive, is simply increased. Firing hole 25 is made with ample vertical clearance between doors 26, and upper surface 31 of hole 25, so that no interference can occur between door 26 and surface 31, 95 when the locomotive wheels have been worn, or turned down to their minimum allowable diameter. In Figs. 2 and 5 this platform is shown with a wide barrier, and a narrowed rear platform, which construction 100 is preferable in locomotives of the type shown in Fig. 2. Bracing may also be modified as shown in Fig. 3, by struts 33 being carried upwardly and rearwardly, to connect with the tender cab, any construction 105 being permissible which will allow ample headroom for entering or leaving the locomotive platform by way of opening 36 between the locomotive and the tender. The platform, or platform and barrier, may also be constructed integral with deck of the tender thereby avoiding the use of a 110 separate device.

In the types of locomotives shown in Figs. 6 and 7, the platform and the barrier are 115 preferably made the same width throughout so that the barrier shall be narrow enough to go between the upper decks of the locomotive cab as shown in Fig. 9.

In Figs. 8 and 9 the holes 37 for the manipulation of grate shaking bars are shown in the barrier instead of the platform, this modification being necessary on account of the location of the shaking bars.

Having thus described my device, I 125 claim:

1. In a device for providing safety to firemen or other persons on locomotive tenders, in combination with the tender, a platform secured to the deck thereof and provided 130

at or near its forward end with an upwardly projecting barrier.

2. In a device as above mentioned in combination, a locomotive tender, a platform secured thereto, said platform projecting forwardly from the tender and provided at or near its forward end with an upwardly projecting barrier.

3. In a device as above mentioned in combination with a locomotive tender, a platform secured thereto and provided at or near its forward end with an upwardly projecting barrier, said barrier being provided with an opening or plurality of openings.

4. In a device as above mentioned in combination, a locomotive tender, a platform secured thereto, said platform projecting forwardly from the tender and provided at or near its forward end with an upwardly projecting barrier, said barrier being provided with an opening or a plurality of openings.

5. In a device as above mentioned in combination with a locomotive tender, a platform secured thereto and provided at or near its forward end with an upwardly projecting barrier, said barrier being provided with an opening or a plurality of openings.

6. In a device as above mentioned in combination with a locomotive tender, a platform secured thereto and provided at or near its forward end with an upwardly projecting barrier, said barrier being secured and braced to the tender by rearwardly projecting braces.

7. In a device as above mentioned in combination with a locomotive tender, a platform secured thereto and projecting forwardly from the tender and provided at or near its forward end with an upwardly projecting barrier, said barrier being secured or braced to the tender by rearwardly projecting braces.

8. In a device as above mentioned in combination with a locomotive tender, a platform secured thereto and provided at or near its forward end with an upwardly projecting barrier, said barrier being provided with an opening or a plurality of openings.

9. In a device as above mentioned in combination, a locomotive tender, a platform secured thereto, said platform projecting forwardly from the tender and provided at or near its forward end with an upwardly projecting barrier, said barrier being provided with an opening or a plurality of openings and secured or braced to the tender tank by rearwardly projecting braces. 45

10. In a device as above mentioned in combination with a locomotive tender, a platform secured thereto and provided at or near its forward end with an upwardly projecting barrier, said barrier being provided with an opening or a plurality of openings and secured or braced to the tender tank by rearwardly projecting braces. 50

11. In combination with a locomotive tender, a platform with a barrier secured thereto, said platform and barrier being provided with an opening or a plurality of openings for the manipulation of devices on the locomotive. 55

12. In combination with a locomotive tender, a platform with a barrier secured thereto, said platform and barrier being provided with an opening or a plurality of openings for the manipulation of devices on locomotive, said barrier being provided with rearwardly projecting braces securing the barrier to tender tank. 60

13. In a device as above mentioned in combination with a locomotive tender, a platform and an upwardly projecting barrier secured thereto, suitable openings in the platform and the barrier for the manipulation of devices on locomotive, a ledge secured to the barrier adapted to project beneath the

70 firing doors of the locomotive, side barriers to prevent coal from being spilled side-wise, and rearwardly projecting braces to secure and brace the barrier to the tender tank. 75
